J. H. Ganett

UNITED STATES PATENT OFFICE.

EDWIN BROWN, OF LEOMINSTER, MASSACHUSETTS.

IMPROVEMENT IN ATTACHING TRACES TO WHIFFLETREES OF VEHICLES.

Specification forming part of Letters Patent No. **50,682**, dated October 31, 1865.

To all whom it may concern:

Be it known that I, EDWIN BROWN, of Leominster, in the county of Worcester and State of Massachusetts, have invented certain new and useful Improvements in Mode of Attaching Traces to Whiffletrees of Vehicles; and I do hereby declare that the following description, taken in connection with the accompanying drawings, hereinafter referred to, forms a full and exact specification of the same, wherein I have set forth the nature and principles of my said improvements, by which my invention may be distinguished from all others of a similar class, together with such parts as I claim and desire to have secured to me by Letters Patent.

It has long been desirable to secure an attachment for the traces to the whiffletrees of vehicles which would permit of their being easily disengaged therefrom in unharnessing, and also, in cases of accidents, allow of an instant release of the horse from the shafts. Many arrangements of devices have heretofore been invented for this purpose, some of which have been partially successful, but, however, owing to their complication and uncertain operation, have not been generally adopted. The advantages of so securing the traces to whiffletrees are manifest, and need not be herein specified, and they are greatly increased when breeching-hooks are used from which the straps can disengage themselves by the simple forward movement of the horse within the shafts.

The present invention, therefore, consists in so arranging devices for the fastening of traces to whiffletrees that the traces can be simultaneously and instantly unfastened at pleasure. I accomplish this result by inserting in each end of the whiffletree, lengthwise, therewith a sliding spring-bolt moving in suitable bearings. These bolts project from each end of the whiffletree, and have bearings in sockets of cap or plate secured by connecting-bars to the whiffletree. Between these caps and the two ends of the whiffletree the traces are placed, the bolts passing through an aperture in the same to the said caps. Thus, by connecting the two sliding bolts by any suitable strap or other device passing up through the bottom of the vehicle, it is evident that by simply pull-

ing the said strap the bolts will be instantly disengaged from the traces when desired.

In the accompanying plate of drawings my improvements are represented, Figure 1 being a plan or top view, and Fig. 2 a central longitudinal vertical section of the same.

a a in the accompanying drawings represent a portion of a whiffletree, to one end of which is secured my improved trace-fastening, arranged as follows, viz: *b b* is a sliding bolt, placed lengthwise in the whiffletree, projecting from the end thereof, and with bearings in the end plate, *c*, and projection *d* of the plate *f*. The outer end, *p*, of this bolt *b* has a bearing and seat in a socket, *g*, of the cap or plate *l*, securely attached to the whiffletree by a connecting-bar, *m*, and at sufficient distance therefrom to allow of the insertion of the trace *n* between the said cap and whiffletree. *o o* is a spiral spring wound around the bolt *b* and placed between the bearing *d* and cross-bar or rod *p* attached to or forming a part of the bolt *b*, which rod *p* passes out through the slot *r* of the plate *f*, and has a suitable knob or handle, *s*, at the end thereof for the more convenient sliding of the bolt in and out of its socket-seat *g* of the said cap *l*, the spring *o*, however, causing by its elastic force the immediate replacement of the bolt in its cap *l* after having been drawn out of the same.

Having first moved the bolt out of its socket-seat *g* a sufficient distance, and then placed the proper end of the trace in the space *t* between the cap and whiffletree, with its aperture *x* in the same plane with the bolt, by releasing the bolt it is evident that it will then be forced back by its spring to its seat, and passing through the said aperture in the trace will thereby firmly and securely hold the same as desired, and as is apparent without further description.

The advantages of the above arrangement of devices for a fastening for harness-traces are many, among which may be enumerated the following, viz: No wear of the trace is caused, as the aperture therein may be protected in a variety of ways, such as by eyelets, &c.; its strength, simplicity of construction and operation, and non-liability of the trace ever becoming unfastened, except when desired.

The peculiar form and arrangement in which my improvements have been represented and described, it is apparent, may be greatly varied without departing from the principles of my present invention, and by attaching my improved fastening to each end of the whiffletree and simply connecting the two sliding bolts by a strap or other suitable means, running around friction and guiding rollers, and passing up through the bottom of the vehicle, the two bolts can be instantaneously withdrawn from the traces by simply pulling on the connecting-strap above referred to.

It may be also here remarked that the advantages of my improved trace-fastening are greatly increased when breeching-hooks, such as have been described in the specification accompanying my application for Letters Patent on the same, bearing even date herewith,

are used, as in that case to release the horse from the shafts it is only necessary to raise the connecting-strap of the trace-fastenings, as described, the breeching-straps unfastening themselves as the horse then moves forward within the shafts.

Having thus described my improvements, I shall state my claim, as follows:

As a new article of manufacture, spring-bolts for attaching to and detaching traces from whiffletrees, arranged within a casing which is provided with bearings and a protecting-cap, for operation substantially as shown and described.

EDWIN BROWN.
